TOBACCO LATH

Paul E. H. Droemer, Hartford, Conn.

Application May 12, 1947, Serial No. 747,352

1 Claim. (Cl. 294—5.5)

1

This invention relates to tobacco laths.

An object of this invention is to provide a means for supporting tobacco leaves for drying thereof, which will clamp the stems of the leaves and hold the leaves spaced from each other so as to facilitate their drying.

Another object of this invention is to provide a tobacco lath which includes two hingedly connected together clamping members, with one member formed with a pair of spaced jaws, and the other member formed with a single jaw engageable between the pair of jaws to thereby effect a bend in the stem of the leaf. With a construction of this kind, stems of different thicknesses may be secured between the same clamping members, it being understood that the clamping members are of very substantial length so that a substantial number of leaves may be clamped in side by side relation with the stems bent slightly by the pair of clamping jaws by pressure of the single jaw.

A further object of this invention is to provide a tobacco lath of this kind having hinges projecting above the clamping jaws so that the hinges will not interfere with insertion of leaves, the hinges being spring-urged to hold the jaws in clamping position.

With the above and other objects in view, my invention consists in the arrangement, combination and details of construction disclosed in the drawing and specification, and then more particularly pointed out in the appended claim.

In the drawing,

Figure 1 is a plan view of a tobacco lath constructed according to an embodiment of this invention,

Figure 2 is a detail side elevation of the device, Figure 3 is a sectional view taken on the line 3—3 of Figure 1,

Figure 4 is a fragmentary sectional view taken on the line 4—4 of Figure 3,

Figure 5 is a fragmentary sectional view taken on the line 5—5 of Figure 1.

Referring to the drawing, the numerals 10 and 11 designate generally a pair of tobacco leaf clamping members which are each of elongated configuration. The clamping member 10 comprises a rear vertical plate 12 which has extending therefrom a pair of right angularly disposed jaws 13 and 14.

The outer or forward edge of the jaw 13 is beveled as indicated at 15, and the outer edge of the jaw 14 is beveled as indicated at 16.

The outer movable jaw 11 which is of T-shape comprises an elongated plate or head 17 which

2

has extending from the inner side thereof a pair of elongated strips 18 and 19, forming therebetween an inwardly opening channel 20.

A cushion member 21 projects from the inner edges of the channel forming plates or jaws 18 and 19, and is formed with a stem 22 engaging in the channel 20. The two clamping members 10 and 11 are adapted to be hingedly secured together by a series of upstanding hinge members generally designated as 23. Each hinge member 23 includes a stationary leaf 24, secured at its lower end to the jaw member 10, and extending upwardly and outwardly therefrom so that the axis of the barrel 25 will be substantially coplanar with the jaws 15 and 16.

The hinge 23 also includes an outer leaf 26, fixed to and extending upwardly and inwardly from the upper edge of the plate 17, and formed at its upper end with hinged barrels 27 through which a pintle 28 loosely engages. A spring 29 is disposed about the pintle 28, between the inner barrels 27, and has one end 30 thereof anchored to the rear leaf 24, and the other end 31 thereof anchored to the outer or forward leaf 26.

The spring 29 is adapted to constantly urge the outer movable jaw 11 toward the inner stationary jaw 10. By providing a hinge connection between the two jaws or clamping members 10 and 11, as hereinbefore described, the stem S of a tobacco leaf may be extended partly above the clamping members in the angle formed between the leaves 24 and 26 of the hinges.

In the use and operation of this lath, the tobacco leaves may be engaged with the inner jaw member 10, and if desired the lath may be laid on a table with the outer jaw 11 opened and the stems S of the tobacco leaves may be extended across the two right angle jaw forming members 13 and 14 of the jaw or clamping member 10. The outer clamping member 11 may then be released, and the pressure or tension of the spring 29 will be such as to form a bend, as indicated at 32, in the stem of the leaf between the two jaws 13 and 14. In this manner the leaf L will be firmly clamped to the lath so that this lath may then be suspended from a suitable support, with the leaves secured thereto in slightly spaced relation. This procedure will eliminate the bunching or binding of the leaves together for drying in the drying barn, and will accelerate the drying period during which the leaves are dried.

I do not mean to confine myself to the exact details of construction herein disclosed, but claim all variations falling within the purview of the appended claim.

What I claim is:

A tobacco lath comprising a pair of elongated clamping members, one of said members being channel-shape and the other of said members being T-shape in transverse section and comprising a head and a stem said stem forming a single jaw engageable between the sides of the channel, a flexible resilient cushion member carried by said single jaw, and means hingedly securing said members together whereby tobacco leaf stems of various thicknesses may be clamped for sliding movement along the length of said lath. 10
